(57) **CLAIM**

The ornamental design for an adjustable crimping guide die, as shown and described.

DESCRIPTION

FIG. 1 is a perspective view showing my new design for an adjustable crimping guide die.

FIG. 2 is a front view thereof,

FIG. 3 is a rear view thereof,

FIG. 4 is a right side view thereof,

FIG. 5 is a left side view thereof,

FIG. 6 is a top view thereof; and,

FIG. 7 is a bottom thereof.

The broken lines shown in the drawings are included for the purpose of illustrating environmental structure and form no part of the claimed design.
